UNITED STATES PATENT OFFICE.

EDWARD F. FEDERHART, OF PASADENA, CALIFORNIA.

PLAITING MACHINE.

Application filed October 3, 1921. Serial No. 504,867.

An object of this invention is to provide means whereby fabrics may be conveniently, rapidly and perfectly plaited.

Another object is to make provision whereby the fabrics may be plaited with plaits of any desired size or form.

The invention is broadly new, basic and pioneer in that I provide two internally heated hollow rollers with external grooves or ridges formed according to the plaiting required, and adapted to conform to each other, and said grooved rollers are mounted in adjustable relation to each other to accommodate different thicknesses of material passing between said rollers.

The rollers may be changed to produce plaiting of different styles and widths and in this connection I have made provision whereby the rollers may be correspondingly provided with various ridged surfaces.

An object is to provide means whereby numerous forms and sizes of plaiting may be produced with a minimum installation.

Strength, cheapness, convenience of manufacture and convenience of changing from one to another form of plaits are other objects.

The invention is broadly new, basic and pioneer in that heretofore there has been no plaiting machine in which rollers having crimped surfaces cooperate to form crimps in material adapted for clothing.

Nor are there any crimping machines having rollers with changeable toothed, grooved or ridged peripheries nor in which there are interchangeable teeth for any such periphery.

An object is to provide such a machine in the most simple and effective form.

Other objects, advantages and features of invention may appear from the accompanying drawings, the subjoined detail description and the appended claims.

The accompanying drawings illustrate the invention.

Figure 1 is a fragmental elevation of one end of a plaiting machine constructed in accordance with this invention in its simplest form.

Fig. 2 is fragmental plan of the machine shown in Fig. 1.

Fig. 3 is a vertical section on line x^3 , Figs. 1 and 2.

Fig. 4 is an end elevation of a form of roller adapted for interchangeable plaiting

teeth, a set of which is shown secured in place.

Fig. 5 is a broken section on line x^5 , Fig. 4.

Fig. 6 is an end elevation of a form of roller having individual detachable teeth.

Fig. 7 is a section on line x^7 , Fig. 6, showing one end of said roller.

Fig. 8 is a fragmental view showing one tooth in place on the head of said roller; 65 a different form of spring being used for the mounting of said tooth.

Fig. 9 is a section on line x^9 , Fig. 8.

Arrows in the various views indicate the direction of sight. 70

The frame 1 is constructed to support two hollow rollers 2, 3; said rollers being provided with longitudinal plaiting teeth which are arranged to mesh together. Various forms of toothed or grooved periphery may 75 be used and in Figs. 1-3 the teeth 4 are shown cast on the periphery of the hollow rollers.

The roller 3 is mounted on supporting radial arms 5, 6 which by means of a hinge 80 7 and spring 8 hold the roller 3 parallel to and in resilient contact with roller 2, thus to accommodate various thicknesses of material. In Fig. 1 one thickness of material a , b , is shown as being plaited between said 85 rollers.

Steam is carried into the interior of the rollers 2, 3 through the hollow axles 9 and 10 which serve as steam pipes and are fitted with suitable unions and stuffing boxes 11, 90 12. Pet cocks 13 are provided at one end near the peripheral wall of each roller for drainage purposes.

The rollers are revolved by suitable driving mechanism shown in Figs. 2 and 3, as 95 a pulley 14.

The steam inlet is governed by valves 15 and 16.

In Figs. 4 and 5 the roller 17 comprises a peripherally smooth hollow steam heated 100 cylinder 18 adapted to be fitted with a variety of detachable hollow shells, one of which is shown at 19, open from end to end and provided on their peripheries with corresponding teeth 20 of any size and shape 105 necessary for the required work and being interchangeable. A head 21 having a flange 22 is screwed into and closes the internally threaded open end of cylinder 18. The flange forms an abutment for one end of 110

the shell which is held at the other end by any suitable means, as the screw 23 having an eccentric head projecting radially thus forming a latch to removably hold the shell 5 in place.

In Figs. 6, 7, 8 and 9 the fluted periphery of the hollow cylinder 24 is provided with grooves 25 adapted to receive individual teeth 26 that are conformed on their inner 10 sides to the groove and may be of any predetermined form adapted to the operation of the plaiting on their outer sides. In the form shown the inner sides 27 of the teeth are semi-circular and the outer faces are flat 15 from end to end thus forming on each of the rollers toothed surfaces corresponding to that indicated in Fig. 6. The individual teeth 26 are held in their seats respectively by connectors 28 which are fixed in projecting lugs 29 of the individual bar-like teeth 26 that extend from end to end of the cylinder.

Said connectors are also provided with the eyes 30 fastened by screws 31 to the head 32 25 of the hollow cylinder. The connectors 28 may be fixed to the lugs 29 by any suitable means and are shown as being riveted thereto. In Figs. 8 and 9, the connectors are represented as helical springs 33 fixed to 30 projections 29 of the teeth, and connected by screws 34 to retainers 35 that are fixed to the head 32.

The base 36 of the frame is provided with two rigid uprights 37, 38. The upright 37 35 is provided at its upper end with a stationary bearing 39, and said uprights 37, 38 are provided with co-axial stationary bearings 39, 40 to receive the co-axial stub shaft 41, and the hollow shaft 9 of the lower cylinder 40. The upright 38 is provided with an upwardly projecting arm 42 which has a support 43 that may be a hollow bearing on which is mounted the oscillating bracket 44 having the radial arms 5 and 6 provided at 45 its ends with the journal bearings 45, 46 in which I mount the shafts of the upper cylinder provided with teeth meshing with the teeth of the lower cylinder.

The spring 8 operates upon the oscillator to depress the roller toward and into contact with the corrugated or fluted periphery of the roller 2. By the construction shown the fluting iron or upper roller 3 may be swung up away from the lower roller 2 and the material to be plaited is inserted over the lower roller and the upper roller allowed to be brought into position shown in Fig. 1, and the rollers heated by steam are revolved by power applied to the pulley 14, and the material is quickly plaited to the form produced in the well known manner.

By mounting the upper roller 3 on the radial arms 5, 6, and pivoting such arms at

one end as shown in Fig. 2 provision is made whereby only a portion of a piece of fabric 65 may be plaited if desired, i. e., if only one edge of a piece of fabric is to be plaited such fabric may be inserted between the rollers to the depth to which the fabric is to be plaited and then run through the device, and that portion of the fabric that is not to be plaited may freely extend out of one end of the rollers without interference by the roller supporting means at such end. 70 I claim.

1. A plaiting machine comprising two toothed rollers adapted to mesh with each other, and to crimp into plaits a fabric run between them; one of said rollers being stationed on a support; and a radius arm oscillatable on said support; the second of said rollers being journaled to said radius arm and adapted to yieldingly press a fabric toward the stationed roller. 80

2. A plaiting machine comprising uprights; a toothed roller mounted in said uprights; an oscillating bracket hinged to one of said uprights; and a toothed roller journaled in said bracket and adapted to cooperate with the other roller for the purpose set forth. 85

3. A plaiting machine comprising a hollow cylinder, a cap for one end of said cylinder; means to introduce steam into the cylinder; a toothed shell to fit said cylinder, and means to fasten said shell on the cylinder. 90

4. A plaiting machine comprising in combination, a hollow cylinder open at one end and closed at the other end, of a cap threaded to the open end of the cylinder and provided with a steam pipe; a toothed shell mounted on the cylinder and abutting against the cap, and means for securing the other end of the shell against removal from the cylinder, said cylinder being adapted to revolve and to mesh with the corresponding cylinder. 100

5. In a plaiting machine the combination with a cylinder of a toothed shell for said cylinder; a stop for said shell at one end of said cylinder and a screw screwed into the other end of the cylinder and having an eccentric projection to retain the shell on the cylinder. 110

6. A plaiting machine comprising two toothed rollers adapted to mesh with each other and to crimp a fabric run between them; a stationary support on which one of said rollers is journaled, and a radius arm oscillatable on the stationary support; the second roller being journaled thereon; and means to revolve one of said rollers. 115

In testimony whereof, I have hereunto set my hand at Los Angeles, California, this 26th day of September, 1921.

EDWARD F. FEDERHART.
